UNITED STATES PATENT OFFICE.

EDWIN V. SWANGREN, OF MAYWOOD, ILLINOIS, ASSIGNOR TO AMERICAN CAN COMPANY, OF NEW YORK, N. Y., A CORPORATION OF NEW JERSEY.

FEED MECHANISM FOR CAN-HEADS AND CAN-BODIES.

1,002,337.

Specification of Letters Patent.

Patented Sept. 5, 1911.

Application filed May 20, 1910. Serial No. 562,406.

To all whom it may concern:

Be it known that I, EDWIN V. SWANGREN, a citizen of the United States, residing in Maywood, in the county of Cook and State 5 of Illinois, have invented a new and useful Improvement in Feed Mechanism for Can-Heads and Can-Bodies, of which the following is a specification.

My invention relates to improvements in 10 can head and can body feed mechanism for can seaming or other machines.

The object of my invention is to provide a can head and can body feeder for automatically feeding can heads and can bodies 15 to continuously moving carriers of double seaming or other machines, which will be of a simple, efficient and durable construction and operate to automatically feed the can bodies to the can body receiving pockets 20 of the continuously moving carrier from a can chute or runway, and also automatically feed the can heads from a pile or stack in a can head holder and deliver the same automatically to the can head seats of the continuously moving carrier, and in which 25 both the feed of the can heads and can bodies will be automatically controlled by the presence or absence of the other, so that a can head will not be delivered to the carrier unless a can body is also delivered or 30 in position to be delivered to the carrier, and so that a can body will not be delivered to the carrier unless a can head is also delivered thereto or in position to be delivered 35 thereto.

My invention consists in the means I employ to practically accomplish this object or result, the same comprising certain novel constructions of parts and devices and certain 40 novel combinations of parts and devices as herein shown and described and more particularly specified in the claims.

In the accompanying drawing forming a part of this specification, Figure 1 is an end 45 elevation, partly in vertical section, of a can head and body feed mechanism embodying my invention. Fig. 2 is a detail elevation partly in vertical section. Fig. 3 is a detail elevation showing a portion of the can body feed chute and certain connected parts. Fig. 4 is a detail section on line 50 4-4 of Fig. 2. Fig. 5 is an enlarged detail section on line 5-5 of Fig. 1 and Figs. 6 and 7 are detail views of parts hereinafter 55 to be described.

In the drawing, 1 represents a portion of the frame of a can seaming or other machine having a continuously revolving carrier 2, furnished with a plurality of can body receiving pockets 3, and also a plurality of can head receiving seats 4, to which pockets and seats the can bodies 5 and can heads 6 are to be automatically fed or delivered as the carrier rotates continuously, and 7 is the shaft of the carrier 2. These 65 parts may be of any suitable or known construction and need no further description.

8 is a can body feed chute or runway, preferably arranged in an inclined position, and from which the can bodies are to be 70 fed or delivered one by one into the pockets 3 of the carrier 2. The can body feed chute 8 is provided with a can body feeder 9, preferably a finger or lever adapted to project into the path of the can bodies in the 75 chute 8 and to permit the feed or delivery of the lowermost can body in the chute into one of the pockets 3 of the carrier 2 when the feeder 9 is withdrawn.

The can head holder 10 in which the can 80 heads 6 are placed in a pile or stack, as shown in Fig. 2, is preferably arranged in an inclined position, and is preferably of semi-cylindric form, and provided with a fixed lip 11 to support the pile of can heads 85 at one edge, and with a rotary feeder 12, having two sets of can head supporting teeth 13 and 14, the teeth on one set being alternately arranged in respect to those of the other, the one set being separated or 90 spaced apart from the other set the thickness of a can head, so that as the feeder 12 rotates, the pile of can heads in the holder 10 will be alternately supported by a tooth of the lowermost set 13 and next by a tooth 95 of the uppermost set 14, thus causing the lowermost can head of the pile to be discharged upon the inclined chute 15 at each partial turn of the rotary alternately toothed, star shaped feeder 12. The shaft 100 16 of the can head feeder 12 is provided with a bevel gear 17, engaging a bevel gear 18 on the shaft 19 of the star wheel 20 by which the feeder 12 is intermittently rotated as required. The can heads pass by 105 gravity from the inclined chute 15 into one of the pockets 21 of a continuously rotating can head delivery wheel 22, which is preferably driven from the shaft 7 of the carrier 2 through intermeshing gears 23, 110

24, 25, 26, to cause the can head pockets of the delivery wheel to register with the can body pockets and can head seats of the carrier 2 as the carrier 2 and wheel 22 revolve continuously. The can head delivery wheel 22 is preferably formed of a sheet metal ring having projecting members 27 and a back plate or disk 28 separated from the ring by the thickness of a can head, the 10 can head pockets 21 being separated from each other by intervening segmental blocks 29. A stationary curved guide or guard 30 supports the can head in the pocket of the delivery wheel 22 as the wheel 22 revolves. 15 The guide or guard 30 is furnished with a flange 31 to keep the can head in an upright position as it is moved by the delivery wheel 22 into the can head seat 4 of the carrier 2 as the carrier 2 and delivery wheel 22 20 rotate.

Each of the can head pockets 21 of the delivery wheel 22 is furnished with a movable feed-controller 32, the position of which is governed by the presence or absence of a can 25 head 6 in the pocket 21 of the delivery wheel 22. The movable feed-controller 32 preferably consists of a sliding pin having a disk 33 and mounted in a hollow stud or sleeve 34 secured to the delivery wheel 22, and furnished with an annular groove 35 for engagement with a retaining spring 36, which 30 serves to hold the feed-controller in normal position while permitting it to be slipped inward by a cam or arm 37 on the stationary bracket 38 as the projecting end of the feed-controller is carried past said cam 37 in the rotation of the delivery wheel 22. The cam 37 is preferably furnished with a yielding backing or spring 39 to cushion the engagement 35 of the feed-controller therewith and to 40 permit the cam 37 to move out of the path of the feed-controller in case a can head is present in the pocket 21 and thus prevents any inward movement of the feed-controller. 45 The feed-controller 32 is furnished with a collar 40 to limit the inward movement of the feed-controller. In case a can head 6 is in the pocket 21 of the delivery wheel 22, the can head itself prevents any 50 inward sliding movement of the feed-controller 32, the spring 39 permitting the yielding cam or arm 37 to move out of the way of the feed-controller as it passes. In case a can head 6 is in the pocket 21 of the can head delivery wheel 22 in position to be 55 delivered into the can head seat 4 of the carrier 2, the can head governed feed controller 32 remains in its normal position, as shown in Figs. 2 and 5, and as the delivery wheel 60 22 continues its rotation, the disk 33 on the feed-controller engages the cam arm 41 of the can body feed operating lever 42, which is connected by a link 43 to the can body feeder 9, and thus withdraws said feeder 9 65 and permits the lowermost can body in the

can body feed chute 8 to be fed into the can body pocket 3 of the carrier 2. In case no can head is in the pocket 21 of the delivery wheel 22 when such pocket passes the movable cam or lever 37, said cam pushes the 70 feed-controller 32 inward, so that the disk 33 of the feed-controller engages the laterally offset arm 44 of the can body feeder operating lever 42, and thus holds the can body feeder 9 closed and prevents the can bodies which may normally ride against the outer periphery of the carrier 2 from dropping into the can body pocket 3 thereof as the carrier rotates, the disk 33 being thus moved 75 out of line with the operating arm 41 of the lever 42. The operation of the can body feeder 9 is thus controlled by the can head governed feed-controller mounted on the can head delivery wheel so that no can body can be fed from the can body chute 8 to the 80 pocket of the carrier 2 unless a can head is in position in the corresponding pocket of the delivery wheel 22 to be also delivered to the corresponding can head seat of the carrier 2. This prevents the feed or delivery 85 of a can body to the carrier 2 unless a can head is also delivered into registry with such can body.

To automatically control the feed of the can heads from the holder 10 to the delivery wheel 22 by the presence or absence of can bodies in the can body chute 8 so that no can heads will be fed from the holder 10 unless can bodies are also in position to be fed from the can body chute 8, I provide the can body chute 8 with a can body governed feed-controller 45, consisting preferably of a finger or lever projecting into the path of the can bodies in the chute 8 and adapted to be engaged by the next to the last can body in the chute and to be normally moved out of the way by the gravity of the can bodies passing down the chute as they are discharged therefrom one by one by the can body feeder 9. This can body-governed can head-feed-controller is connected by a link 46 with an arm 47 on the hub 48 engaging a movable forked cam 49 pivoted at 50 to a bracket 51 on the can body chute, and which normally engages the disk 33 of the feed-controller 32, and thus operates to restore the feed-controller 32 to its normal position so that it will engage the star wheel 20, through which the can head feeder 12 is operated by the feed-controller 32 as the delivery wheel 22 rotates. In the event, however, that there are no can bodies in the chute 8 to operate the device 45, and through it the forked cam 49, said forked cam by engagement with the disk 33 moves the feed controller 32 into 100 position to pass the star wheel 20 without engagement therewith and thus prevents the feed of the can head from the holder 10 unless there are can bodies in the chute 8 also 105 in position to be fed.

A stationary cam or projection 53 on the frame serves by engagement with the disk 33 of the feed-controller 32 to restore each of the feed-controllers 32 on the delivery 5 wheel 22 to normal position.

The delivery chute 15 extends at an angle to the plane of the delivery wheel 22 and intersects the same centrally or at a plane radially inside the can head pockets of the 10 carrier so that the can heads are delivered to the wheel relatively near the center or axis thereof and where the travel is slow as compared with the rim or peripheral portion of the wheel. This materially facilitates 15 the certain and accurate delivery of the can heads from the chute into the pockets of the delivery wheel 22.

I claim:—

1. The combination with a movable carrier 20 having a plurality of can body receiving pockets and a plurality of can head receiving seats, of a can body chute, a can body feeder, a can head holder, a can head feeder, a can head delivery wheel having a plurality of can head receiving pockets into which the can heads are delivered one by one as they are discharged from said holder by said can head feeder, and can head governed means on said delivery wheel for 25 controlling the operation of said can body feeder, substantially as specified.

2. The combination with a can body chute and can body feeder, of a can head holder and can head feeder and can head governed 30 means for controlling the operation of said can body feeder, substantially as specified.

3. The combination with a can body chute and can body feeder, of a can head holder and can head feeder and can head governed 35 means for controlling the operation of said can body feeder, and can body governed means for controlling the operation of said can head feeder, substantially as specified.

4. The combination with a continuously 40 rotating carrier having a plurality of can body pockets and a plurality of can head seats, of a can body chute, a can body feeder, a can head holder, a can head feeder, a continuously 45 rotating can head delivery wheel having a plurality of can head pockets, a chute for delivering the can heads as they are discharged from said holder to the pockets of said delivery wheel and a plurality of can head governed feed controllers mounted 50 on said carrier, substantially as specified.

5. The combination with a continuously 55 rotating carrier having a plurality of can body pockets and a plurality of can head seats, of a can body chute, a can body feeder, a can head holder, a can head feeder, a continuously 60 rotating can head delivery wheel having a plurality of can head pockets, a chute for delivering the can heads as they are discharged from said holder to the 65 pockets of said delivery wheel and a plu-

rality of can head governed feed-controllers mounted on said carrier, and a movable cam for changing the positions of said movable feed-controllers on said delivery wheel as the same rotate, substantially as specified. 70

6. The combination with a continuously 75 rotating carrier having a plurality of can body pockets and a plurality of can head seats, of a can body chute, a can body feeder, a can head holder, a can head feeder, a continuously 80 rotating can head delivery wheel having a plurality of can head pockets, a chute for delivering the can heads as they are discharged from said holder to the pockets of said delivery wheel and a plurality of can head governed feed controllers mounted 85 on said carrier, and means for actuating said feed-controllers as said delivery wheel rotates, substantially as specified.

7. The combination with a continuously 90 rotating carrier having a plurality of can body pockets and a plurality of can head seats, of a can body chute, a can body feeder, a can head holder, a can head feeder, a continuously 95 rotating can head delivery wheel having a plurality of can head pockets, a chute for delivering the can heads as they are discharged from said holder to the pockets of said delivery wheel and a plurality of can head governed feed controllers mounted 100 on said carrier, means for actuating said feed-controllers as said delivery wheel rotates, and an operating lever for said can body feeder adapted to be engaged by said can body feed-controllers on said delivery wheel, substantially as specified.

8. The combination with a continuously 105 rotating carrier having a plurality of can body pockets and a plurality of can head seats, of a can body chute, a can body feeder, a can head holder, a can head feeder, a continuously 110 rotating can head delivery wheel having a plurality of can head pockets, a chute for delivering the can heads as they are discharged from said holder to the 115 pockets of said delivery wheel and a plurality of can head governed feed controllers mounted on said carrier, means for actuating said feed-controllers as said delivery wheel rotates, an operating lever for said 120 can body feeder adapted to be engaged by said can body feed-controllers on said delivery wheel, a can body governed feed-controller adapted to be engaged by can bodies in said can body chute, and a movable device actuated thereby and adapted to engage said feed-controllers on said delivery wheel to control the operation of said can head feeder, substantially as specified.

9. The combination with a continuously 125 rotating carrier having a plurality of can body pockets and a plurality of can head seats, of a can body chute, a can body feeder, a can head holder, a can head feeder, a continuously 130 rotating can head delivery wheel

having a plurality of can head pockets, a chute for delivering the can heads as they are discharged from said holder to the pockets of said delivery wheel and a plurality of can head governed feed controllers mounted on said carrier, a can body governed feed-controller adapted to be engaged by the can bodies in said can body chute, and a movable device connected therewith 5 and adapted to be engaged by said feed controller on said can head delivery wheel, substantially as specified.

10. The combination with a continuously rotating carrier having a plurality of can body pockets and a plurality of can head seats, of a can body chute, a can body feeder, a can head holder, a can head feeder, a continuously rotating can head delivery wheel having a plurality of can head pockets, a chute for delivering the can heads as they are discharged from said holder to the pockets of said delivery wheel and a plurality of can head governed feed controllers mounted on said carrier, operating 15 means for said can body feeder having a movable device in the path of said feed controllers on said delivery wheel, substantially as specified.

11. The combination with a continuously rotating carrier having a plurality of can body pockets and a plurality of can head seats, of a can body chute, a can body feeder, a can head holder, a can head feeder, a continuously rotating can head delivery wheel 20 having a plurality of can head pockets, a chute for delivering the can heads as they are discharged from said holder to the pockets of said delivery wheel and a plurality of can head governed feed-controllers mounted on said carrier, operating means for said can body feeder having a movable device in the path of said feed-controllers on said delivery wheel, a can body governed feed-controller and connecting means for actuating said feed-controllers on said delivery wheel thereby, substantially as specified.

12. The combination of a holder for a stack or pile of articles to be fed, having a stationary supporting lip at one edge thereof and a rotary star shaped feeder having two sets of alternately arranged teeth spaced apart the thickness of the articles to be fed, the teeth of each set alternately supporting the pile of articles in the holder and causing the lowermost one to be released at each turn, a delivery wheel having a plurality of pockets and an inclined chute for delivering the articles as they are discharged one by one from said holder into the pockets of said wheel, substantially as specified.

13. The combination of a holder for a stack or pile of articles to be fed, having a stationary supporting lip at one edge thereof and a rotary star shaped feeder having two

sets of alternately arranged teeth spaced apart the thickness of the articles to be fed, the teeth of each set alternately supporting the pile of articles in the holder and causing the lowermost one to be released at each turn, a delivery wheel having a plurality of pockets, and an inclined chute for delivering the articles as they are discharged one by one from said holder into the pockets of said wheel, said delivery wheel being provided with a series of movable feed-controllers, one for each pocket, substantially as specified. 70

14. The combination of a holder for a stack or pile of articles to be fed, having a stationary supporting lip at one edge thereof and a rotary star shaped feeder having two sets of alternately arranged teeth spaced apart the thickness of the article to be fed, the teeth of each set alternately supporting the pile of articles in the holder and causing the lowermost one to be released at each turn, a delivery wheel having a plurality of pockets and an inclined chute for delivering the articles as they are discharged one by one from said holder into the pockets of said wheel, said delivery wheel being provided with a series of movable feed-controllers, one for each pocket, and a continuously revolving carrier having a plurality of seats into which the articles are delivered one by one by said delivery wheel, substantially as specified. 80

15. The combination with a continuously revolving upright carrier turning on a horizontal axis and provided with a plurality of pockets and seats for two separate articles to be delivered thereto, of a chute and feeder for one of said articles and a holder and feeder for the other of said articles, a continuously revolving delivery wheel having a plurality of pockets, and a chute extending from said holder to said delivery wheel, each of the pockets of said delivery wheel having a feed-controller, substantially as specified. 90

16. The combination with a continuously revolving upright carrier turning on a horizontal axis and provided with a plurality of pockets and seats for two separate articles to be delivered thereto, of a chute and feeder for one of said articles and a holder and feeder for the other of said articles, a continuously revolving delivery wheel having a plurality of pockets, a chute extending from said holder to said delivery wheel, each of the pockets of said delivery wheel having a feed-controller, and means for causing said feed-controllers on said delivery wheel to control the operation of said first mentioned feeder, substantially as specified. 100

17. The combination with a continuously revolving upright carrier turning on a horizontal axis and provided with a plurality of pockets and seats for two separate articles

to be delivered thereto, of a chute and feeder for one of said articles and a holder and feeder for the other of said articles, a continuously revolving delivery wheel having a plurality of pockets, a chute extending from said holder to said delivery wheel, each of the pockets of said delivery wheel having a feed-controller, means for causing said feed-controllers on said delivery wheel to control the operation of said first mentioned feeder, and a second feed-controller governed by

the presence or absence of articles in said first named chute to be fed and means for causing said second feed-controller to control the feed from said holder of the articles therein by said feeder connected therewith, substantially as specified.
